Primary Examiner — Rhea Shields*(74) Attorney, Agent, or Firm* — Syncoda LLC; Feng Ma(57) **CLAIM**

The ornamental design for a charging dock, as shown and described.

DESCRIPTION

2. Charging dock

2.1 is a front view of a charging dock showing the new design;

2.2 is a back view thereof;

2.3 is a left side view thereof;

2.4 is a right side view thereof;

2.5 is a top view thereof;

2.6 is a bottom view thereof;

2.7 is a front, right side, top perspective view thereof;

2.8 is a back, right side, top perspective view thereof;

2.9 is a front, right side, top perspective view thereof; and

2.10 is a front, right side, top perspective view thereof.

In Reproductions 2.9 and 2.10 the purpose of the broken lines show environment only and form no part of the claimed design. Additionally, in 2.3 through 2.10 the length of the cord feature is shown with a symbolic break in its length. The appearance of any portion of the article between the break lines form no part of the claimed design.
